ABSTRACT OF THE DISCLOSURE

A window and frame assembly is formed from a pair of side frame members, a pair of end frame members, and a sheet of flexible, light-transmittant material. The frame members are folded along fold lines parallel to their length, interfolding the sheet material and the ends of the corresponding frame members at the corners. In the preferred embodiment, the end frame members are folded back upon themselves over the side frame members. The sheet material contributes to the overall strength of the assembly, and the frame members are bias cut on the ends to reduce bulk at the corners. Fastening means may optionally be provided at the corners.

The present invention relates to an improved window and frame assembly incorporating flexible, light-transmittant window material.

While windows incorporating transparent, flexible, plastic material are well known in the art, they are often made up of many parts, or lack adequate means for maintaining the window sufficiently tight to prevent sagging and optical distortion. Another difficulty has been excess bulk at the corners, where the side and end frame members overlap, making it difficult to fit the windows into channels.

Generally, the present invention relates to a window and frame assembly including a pair of side frame members, a pair of end frame members, and a generally rectangular sheet of flexible, light-transmittant window material. The frame members are fabricated by strips or longitudinally elongated sections of sheet material, and are folded, along fold lines parallel to their length, over themselves and the window material. In the fully assembled window and frame, the window material cooperates with the frame members to provide strength to the overall structure. Strength is also provided by interfolding the frame members with each other at the corners. This construction is better appreciated by considering the unfolded relationship of the assembly parts, wherein each side frame member overlaps a corresponding end of the end frame members, and the window material overlaps each of the frame members. When the window and frame is assembled, the end frame members are folded over both the window material and the ends of the side frame members, and the side frame members are folded over both the window material and the end frame members.

The invention, both as to its construction and method of manufacture, will be best understood by reference to the following detailed description taken in conjunction with the accompanying drawings in which:

FIGURE 1 is a plan view of the preferred window and frame assembly in fully assembled condition;

FIGURE 2 is an exploded partial view of the window and frame components in unassembled, adjacent relationship;

FIGURE 3 is a partial plan view of the window and frame components in unassembled, overlapped relationship just prior to assembly;

FIGURE 4 is a perspective view of a portion of the window frame in partly assembled relationship;

2

FIGURE 5 is a section view along line 5—5 of FIGURE 1; and

FIGURE 6 is a section view along 6—6 of FIGURE 1.

Referring to FIGURE 1, the present invention comprises a window and frame assembly, indicated generally by reference numeral 10. The assembly includes a pair of side frame members 12 and a pair of end frame members 14 interfolded to form an overall rectangular frame. A sheet of flexible, light-transmittant window material 16 is bounded by the frame members 12, 14, and is interfolded with them and held taught.

As shown in FIGURE 2, in the preferred embodiment the side frame members 12 are each thrice folded over themselves along an outer fold line 20, a central fold line 22, and an inner fold line 24. The fold lines 20, 22, 24 are approximately equidistant, although allowance must be made for the thickness of the frame members. The end frame members 14 are also folded over themselves along an outer fold line 26 and an inner fold line 28. The light-transmittant window material 16 is interfolded with the side frame members along an outer side fold line 30 and an inner side fold line 32, and with the end frame members 14 along an end fold line 34. As shown in FIGURE 2, the side frame members 12 are preferably bias cut between the outer edges and the central fold line 22. This bias cut forms an obtuse inside angle between the outside edge of the side frame members 12 and the end. Between the central fold line 22 and the inner fold line 24, the ends of the side frame members 12 are cut straight, perpendicular to the longitudinal edges. Between the inner fold line 24, and the inner longitudinal edge of the side frame members 12, the ends are preferably bias cut at an angle approximately perpendicular to the bias cut between the outer edge and the central fold line 22.

Similarly, the end frame members 14 are bias cut between the outer longitudinal edges and the inner fold lines 28 to form an obtuse angle between the outer edges and the ends. Between the inner fold line 28 and the inner longitudinal edge, the ends of the side frame members 14 are bias cut approximately perpendicular to the aforesaid bias cut.

FIGURE 3 shows a portion of the frame in properly overlapped but unfolded relationship. The side frame members 12 overlap the end frame members 14 in the manner shown. The tips of the end frame members 14, reach to the central fold lines 22 of the side frame members 12, while the ends of the side frame members 12 are aligned with the inner fold lines 28 of the end frame members 14. As shown in FIGURE 3, the overlapped area forms a parallelogram shape with the inner fold lines 24 of the side frame members 12 traversing the diagonal. The overall shape of the frame members in properly overlapped relationship forms an octagon.

The light-transmittant window material 16 is also preferably bias cut on the corners, as shown in FIGURES 2 and 3, to prevent excess bulk at the corners of the completed window and frame assembly. In properly aligned relationship with the frame members 12, 14 the window material 16 reaches to a point just short of the outer fold lines 20, 26 of the side and end frame members 12, 14, respectively. With the window material 16 thus properly positioned, it will be folded along the fold lines 30, 32, 34 shown in FIGURE 2 when the window and frame are assembled. The bias cuts at the corners of the window material 16 are parallel to the outer bias cuts at the ends of the side and end frame members 12, 14, and traverse or pass near the intersection of the inner side fold lines 32, and the end fold lines 34 of the light-transmittant window material 16. While the particular overlapping relationship, along with the bias cuts on the ends of the side and end frame members

12, 14 can be modified without impairing the strength of the overall window, the advantageous low bulk at the corners of the completed frame will not be realized.

In assembling the frame, the end frame members are first folded over themselves along the outer fold lines 26. The end frame members are then folded over themselves along the inner fold lines 28, interfolding a portion of the window material 16, and enclosing a portion of the side frame members 12 in the area of overlap. Similarly, the side frame members 12 are folded along the outer fold lines 20. They are then folded along the central fold lines 22, interfolding a portion of the window material 16 and partially covering the ends of the end frame members 14. The final fold of the side frame members 12 is made along the inner fold lines 24. As illustrated in FIGURE 4, in the preferred embodiment this fold causes the end frame members 14 to be simultaneously folded back over themselves, strengthening the corners. As also shown in FIGURE 4, the bias cuts at the end of the side frame members 12 and end frame members 14 reduce the bulk of the interfolded corners, since the inner bias cuts abut each other, rather than being unnecessarily overlapped.

After the final fold is made, the overall frame appears as in FIGURE 1. As seen in FIGURES 5 and 6, the end frame members 14 and the side frame members 12 are interfolded with the light-transmittant window material 16, holding it securely in place. Because of this interfolding with the side and end frame members 12, 14, the window material 16 contributes to the overall strength of the frame, and aids in holding it together. Obviously, it is not essential that the window be interfolded twice with the side frame members 12 as shown in FIGURE 6. If this is not desired, the window material 16 may be cut to reach only to the center fold line 22 of the side frame members 12 in unfolded relationship.

While the corners of the frame 10 will generally be held in place by the folding of the frame members, fastening means, such as staples or rivets, may optionally be provided at the four corners to hold the frame in a folded condition. For purposes of illustration, suitable staples 36 are shown at the upper corners of the complete window and frame assembly of FIGURE 1. When such fastening means are employed, they will normally be used at all four corners of the window and frame assembly 10. Normally, however, such fastening means will not be needed. Glue may also optionally be used to help fasten the window material 16 to the frame members, 12, 14. Normally, this will not be required, however, since the interfolded relationship holds the parts in position. However, gluing may be of aid in positioning the parts before final assembly.

Any malleable material having substantial strength may be used to form the frame members 12, 14. Suitable materials include copper, aluminum, light gauge steel, etc., as is well known in the art. The window 16 may be of any flexible, foldable, light-transmittant material, either transparent or translucent, depending upon the desired properties in the window. Suitable materials include films of polyvinylchloride, polyethylene, etc., as is well known to those skilled in the art.

It will be understood that the term "window material" is used in a broad sense, and may also include materials such as wire mesh used in the manufacture of screens. The essential requirements are flexibility and light-transmittancy, a term covering both transparent and translucent materials. While the embodiments described herein are at present considered to be preferred, it will be understood that various modifications and improvements may be made therein and it is intended to cover in the appended claims all such modifications and improvements as fall within the true spirit and scope of the invention.

I claim:

1. A window and frame assembly comprising: a pair of side frame members fabricated of longitudinally elon-

gated sections of sheet material; a pair of end frame members fabricated of longitudinally elongated sections of sheet material; and a flexible, generally rectangular sheet of light-transmittant window material extending between and folded into said members for forming said assembly, said window material being bias cut at the corners to form an overall octagonal shape and to avoid being interfolded with the corners of said frame, said end frame members being folded over said window material and over corresponding ends of said side frame members, and said side frame members, being folded over said window material and over corresponding ends of said end frame members.

2. The window and frame assembly as defined in claim 1 wherein said end frame members are folded at least twice over upon themselves and upon said window material on fold lines parallel to their length.

3. The window and frame assembly as defined in claim 1 wherein said side frame members are folded at least thrice over upon themselves and upon said window material on fold lines parallel to their length.

4. A window and frame assembly comprising: a pair of side frame members fabricated of longitudinally elongated sections of sheet material; a pair of end frame members fabricated of longitudinally elongated sections of sheet material; and a flexible, generally rectangular sheet of light-transmittant material extending between and folded into said members to form said assembly, said side frame members being folded over said window material and over corresponding ends of said end frame members along fold lines generally parallel to their length, and said end frame members being folded over said window material and over corresponding ends of said side frame members along fold lines generally parallel to their length and being folded back over upon themselves along fold lines generally transverse to their length.

5. The window and frame assembly as defined in claim 4 wherein said end frame members are folded at least twice over upon themselves and upon said window material on fold lines parallel to their length, and said side frame members are folded at least thrice over upon themselves and upon said window material on fold lines parallel to their length.

6. The window and frame assembly as defined in claim 5 wherein said frame members are bias cut on the ends to form an overall octagonal configuration when said members are in overlapped relationship prior to folding.

7. The window and frame assembly as defined in claim 6 wherein said frame member sections are bias cut to overlap in a parallelogram-shaped area prior to folding, said end frame members being folded back upon themselves along fold lines traversing the diagonal of said parallelogram.

8. The window and frame assembly as defined in claim 7 further including fastening means for securing the corners of said frame in folded relationship.
